HEAT EXCHANGE APPARATUS

William F. Schroth, Philadelphia, Pa., assignor to
 C. H. Wheeler Manufacturing Co., Philadelphia, Pa., a corporation of Pennsylvania

Application February 16, 1937, Serial No. 125,960

4 Claims. (Cl. 257—43)

This invention relates to heat exchange apparatus of a type involving the flow of liquid through a plurality of tubes of small diameter. Specifically, the invention is applicable to surface condensers.

In heat exchange apparatus, such as surface condensers, in which flow of liquid is caused to take place through relatively small tubes, sediment, carried by the liquid or deposited therefrom as change of temperature of the liquid takes place, will collect within the tubes and particularly adjacent their entrance portions. Sediment of this nature is distinct from scale in that it can be disturbed and removed if the flow through the tubes is caused to take place in an opposite direction. Heretofore, accumulation of such sediment has necessitated shutting down of the apparatus to permit removal of same.

It is the object of the present invention to provide for removal of sediment of the type indicated above by providing a reverse flow of liquid without shutting down the apparatus.

The above object and other objects of the invention, particularly relating to details of construction, will be apparent from the following description read in conjunction with the accompanying drawings in which:

Figure 1 is a side elevation, partly broken away, of a surface condenser embodying the principles of the invention;

Figure 2 is an end elevation of the same, also partially broken away, showing the feed end of the condenser;

Figure 3 is an elevation of the opposite end showing particularly the return box construction;

Figure 4 is an enlarged sectional view showing the arrangement of gate controlling means used in accordance with the invention; and

Figure 5 is a section taken on the plane indicated at 5—5 in Figure 4, but with the gate in its upper position.

The condenser illustrated in the drawings comprises a shell 2 provided with an upper inlet 4 for steam or other vapor which is to be condensed.

The condensate chamber 6 is provided with outlets for the removal of the condensed liquid. Air removal connections are indicated at 8.

At one end of the apparatus there is provided a box 10 divided into upper and lower chambers 14 and 16 by means of a partition 12. Along the vertical center line there is provided a reenforcing web 17 provided with openings 18 furnishing connection between the two sides of the chamber 14, and an opening 20 providing connection between the two sides of the chamber 16.

Extending horizontally from a tube sheet forming the inside wall of chamber 14 are tubes 22, while, extending from the tube sheet forming the inner wall of chamber 16 are tubes 24. The tube sheets may be formed of a single plate.

The tubes 22 and 24 connect with a return box 26, shown in Figure 3, which, though provided with reenforcing webs, nevertheless consists of a single chamber by reason of openings 28 provided in these webs.

Cooling water inlet and outlet conduits 30 and 32, respectively, are provided. The conduit 30 communicates through openings 34 and 36 with the chambers 14 and 16, respectively, while the conduit 32 is in communication with the same chambers through openings 38 and 40. Each of these pairs of openings is controlled by means of a gate 42, as illustrated in Figure 4. Each gate 42 is guided in vertical guide-rails 44 and is arranged to provide liquid-tight contact with the guide-rails and the wall 12. Each of the gates is provided with a plurality of racks 46 meshing with pinions 48 mounted upon a transverse shaft 50 extending through a suitable stuffing box and driven through gears 52 and 54 by a hand wheel 56. In large installations, instead of hand wheels motor driving arrangements, remotely controlled, may be used.

In normal operation the gate controlling the inlet passage will be located in its upper position and the gate controlling the outlet passage in its lower position. As a result the cooling liquid will pass through the opening 36 into the first pass, consisting of tubes 24, thence through the box 26 into the second pass, consisting of tubes 22, whence it will flow out of chamber 14 through passage 38. It will be noted that this flow will provide counter-current action between the incoming steam or vapor and the condensing liquid. At suitable periods the gates on the two sides of the apparatus are oppositely moved, with the result that the chamber 14 will become the inflow chamber and the chamber 16 the outflow chamber, so that the flow through the tubes will be reversed and collected sediment will be washed out through the outlet conduit 32. As soon as such cleanout has been effected, the gates may be again restored to their original positions in order to gain the advantages of the counter-flow arrangement. It will be obvious that the apparatus need not be closed down at any time for the removal of the collected sediment, since the gates may be moved simultaneously in the space of a few seconds to provide reversal of flow. It will be clear that numerous variations may be made

in the specific embodiment of the invention without departing therefrom, also that this invention is by no means limited to a condenser, but is applicable to other cases of heat exchange apparatus in which sediment is to be removed from tubes.

What I claim and desire to protect by Letters Patent is:

1. Heat exchange apparatus including substantially horizontal tubes arranged for the passage therethrough of flowing liquid taking part in the heat exchange, upper and lower chambers, separated by a laterally extending partition, at one end of the tubes, there being two groups of tubes, one group communicating with the upper chamber and the other group with the lower chamber, a common chamber for both groups of tubes at the other end thereof, means for passing fluid through said apparatus successively about the groups of tubes for heat exchange with liquid in the tubes, liquid supply and liquid discharge conduits, and means for alternately connecting said upper and lower chambers with said supply and discharge conduits to provide reversal of liquid flow through the tubes, the connections of the discharge conduit with both of said chambers being at one side of said chambers at the uppermost portions thereof, and the connections of the supply conduit with both of said chambers being at the opposite side of said chambers at the uppermost portions thereof.
2. Heat exchange apparatus including substantially horizontal tubes arranged for the passage therethrough of flowing liquid taking part in the heat exchange, upper and lower chambers, separated by a laterally extending partition, at one end of the tubes, said laterally extending partition having a depressed central portion to provide a lower chamber having side portions extending upwardly above the central portion of the lower chamber to form a concavity receiving the lower central portion of the upper chamber, there being two groups of tubes, one group communicating with the upper chamber and the other group with the lower chamber, a common chamber for both groups of tubes at the other end thereof, means for passing fluid through said apparatus successively about the groups of tubes for heat exchange with liquid in the tubes, liquid supply and discharge conduits, and means for alternately connecting said upper and lower chambers with said supply and discharge conduits to provide reversal of liquid flow through the tubes, the connections of the discharge conduit with both of said chambers being at one side of said chambers at the uppermost portions thereof.

3. Heat exchange apparatus including substantially horizontal tubes arranged for the passage therethrough of flowing liquid taking part in the heat exchange, upper and lower chambers, separated by a laterally extending partition, at one end of the tubes, said laterally extending partition having a depressed central portion to provide a lower chamber having side portions extending upwardly above the central portion of the lower chamber to form a concavity receiving the lower central portion of the upper chamber, there being two groups of tubes, one group communicating with the upper chamber and the other group with the lower chamber, a common chamber for both groups of tubes at the other end thereof, means for passing fluid through said apparatus successively about the groups of tubes for heat exchange with liquid in the tubes, liquid supply and discharge conduits, and means for alternately connecting said upper and lower chambers with said supply and discharge conduits to provide reversal of liquid flow through the tubes, the connections of the discharge conduit with both of said chambers being at one side of said chambers at the uppermost portions thereof.

4. Heat exchange apparatus including substantially horizontal tubes arranged for the passage therethrough of flowing liquid taking part in the heat exchange, upper and lower chambers, separated by a laterally extending partition, at one end of the tubes, said laterally extending partition having a depressed central portion to provide a lower chamber having side portions extending upwardly above the central portion of the lower chamber to form a concavity receiving the lower central portion of the upper chamber, there being two groups of tubes, one group communicating with the upper chamber and the other group with the lower chamber, a common chamber for both groups of tubes at the other end thereof, means for passing fluid through said apparatus successively about the groups of tubes for heat exchange with liquid in the tubes, liquid supply and discharge conduits, and means for alternately connecting said upper and lower chambers with said supply and discharge conduits to provide reversal of liquid flow through the tubes, said last mentioned means comprising upwardly sliding valves arranged to control openings above and below said partition, one controlling flow into both said chambers from the supply conduit and the other controlling flow from both chambers into the discharge conduit, said discharge and supply conduits being located adjacent the opposite ends of said partition at the uppermost portions of the chambers, so that cross flow of liquid through said chambers may be effected when said valves are in intermediate positions.

WILLIAM F. SCHROTH.
